Inventor.

Thomas O. Potter

United States Patent Office.

THOMAS O. POTTER, OF BOSTON, MASSACHUSETTS.

Letters Patent No. 97,116, dated November 23, 1869.

IMPROVEMENT IN SUSPENDERS.

The Schedule referred to in these Letters Patent and making part of the same.

To all whom it may concern:

Be it known that I, THOMAS O. POTTER, of Boston, in the county of Suffolk, and State of Massachusetts, have invented a new and improved Shoulder-Brace and Suspender Combined; and I hereby declare that the following is a full, clear, and exact description thereof, reference being had to the accompanying drawings, making a part of this specification.

A suspender and shoulder-brace combined, consisting of loops passing over each shoulder, and connected together behind by an adjustable strap, each loop being connected to the pantaloons at one point on the sides, is well known; and

My invention consists in an improvement upon this shoulder-brace and suspender, by the addition of two straps in front, one on each side, and two straps behind.

When the first-mentioned shoulder-brace and suspender combined is used with pantaloons which are loose around the waist, the waistband of the pantaloons, being held only at two points, will sag in front and behind, thereby becoming uncomfortable as well as unsightly; and the object of my invention is to remedy this difficulty.

In the drawings—

A A' are the loops; B is the adjustable strap which connects them together so as to brace the shoulders; and C C' and D D are the straps which connect the loops with the pantaloons.

I prefer to connect these straps directly with the loops, and to make the straps C' and D of light web, as they are not intended to support the weight of the pantaloons, but simply to prevent the waistband from sagging.

I do not claim a suspender and shoulder-brace combined, consisting of two loops connected together behind by an adjustable strap, as I am aware that is already patented by B. J. Greely; but

What I do claim as my invention, and desire to secure by Letters Patent, is—

As a new article of manufacture, the suspender and shoulder-brace combined, above described, consisting of two loops, each provided with straps, as described, and connected together behind by an adjustable strap, all substantially as described.

THOMAS O. POTTER.
